FILING DRAWER

Ross R. West, San Francisco, Calif., assignor to
 M. G. West Company, San Francisco, Calif., a
 corporation of California

Application April 12, 1941, Serial No. 388,287

3 Claims. (Cl. 129—32)

This invention relates to filing cabinet drawers, and particularly to a combination of a drawer with a specially constructed type of longitudinally adjustable tiltable follower board of the type shown in my Patents No. 2,272,537, dated Feb. 10, 1942, and 2,238,083, dated April 15, 1941.

The present invention comprises briefly a follower board which normally occupies a vertical position to the drawer bottom; which is adjustable longitudinally of the file drawer and is hinged in the plane of the drawer bottom for backward tilting, and is returnable to vertical position by spring action which can be accurately set to exert any desired pressure.

The instant design, by pivoting the follower plate to a sliding shoe in the bottom of the drawer, completely eliminates the necessity for sliding the contents along the bottom in opening or closing, and yet permits the files to be tilted backwards for inspection or removal against the spring action, with great rapidity and with a minimum of effort; the spring tension, however, not being greater than simply to hold the plate in a vertical position and let it be moved back manually to expand the contents of the drawer.

The adjustment of the spring tension or pressure on the follower plate is necessary to make it possible to accommodate the spring tension to the various loads imposed upon the drawer. For example, in a letter file drawer, fully loaded, the contents weigh approximately 63 lbs. and in a legal sized drawer the contents weigh approximately 76 lbs., when fully loaded, so that the pressure exerted by this follower plate or board to keep the contents of the drawer in a vertical position is variable.

The objects of my invention thus include: the provision of a file drawer follower which is so mounted as to pivot at the bottom of the file drawer, rather than at a point intermediate to the top and bottom of the follower and which at the same time may be readily shifted to any desired point longitudinally of the drawer; the provision of adjustable resilient means for permitting backward manual tilting of said follower board and returning said board to a vertical position against the normal resistance offered by the contents of a file drawer; the provision of a follower support which takes up a minimum of space within the file drawer proper; and the elimination of movable follower parts which occupy space within the filing space and which may damage the file contents.

These and other objects will appear to those

skilled in the art and are exemplary of the uses and advantages of my invention.

In the drawings:

Fig. 1 is a perspective view of the invention embodied in a file drawer;

Fig. 2 is a side view, partially in section, of a file drawer with my follower board;

Fig. 3 is a plan view of my follower plate showing details of its mounting in the file drawer, shown fragmentarily in section;

Fig. 4 is a plan view of the connection between the follower plate and the drawer, with the shoe assembly and bottom channel spaced to illustrate the construction more clearly;

Fig. 5 is a sectional end view of the plate and shoe structures of Fig. 3, taken along the line 5—5 of Fig. 3;

Fig. 6 is a perspective view illustrating a movable divider to be used with my invention; and

Fig. 7 is a fragmentary view of a modified form of divider.

Referring now to the drawings, in Fig. 1, I have shown a perspective view of my device in position in a file drawer. The drawer 1 comprises the conventional front 2, with a pull or handle 4 and two sides 5 connected by a bottom 6 and a low upturned back 7.

The follower plate 8 is mounted on a sliding shoe assembly 9 which is held in a central channel 10 by means to be described hereafter. These means permit moving the shoe 9, together with plate 8, to any desired position along the bottom of the drawer. At the same time, the plate 8 may be tilted backward manually to the position shown in dotted outlines in Fig. 2. The indicated tilting limit of about 25° has been found to be most convenient in ordinary service, but may be changed if desired to suit the individual needs of the user.

In Fig. 3, I have illustrated the follower plate assembly in its preferred embodiment, as it is mounted in the drawer. The plate 8 has a hand grip 10 formed centrally of its reinforced upper edge 11 to facilitate carrying the entire drawer in case it is to be moved outside the filing cabinet, not shown, in which it is normally housed. Plate 8 may also be reinforced along its sides by means such as a rolled edge, 12. At its lower edge, plate 8 is attached to the supporting shoe assembly 9 by means of a hinge pin 13. Hinge pin 13 extends through side journals 14 and a center journal 15 formed integrally with plate 8, and then through inner side journals 16 formed on lateral support arms 17 constituting a part of shoe assembly 9.

Centrally of the shoe assembly 9, these lateral support arms 17 join the shoe 19, which extends downwardly therefrom to fit slidably within a channel 10 fixed in a rectangular depression or seat 21 extending centrally the full length of drawer bottom 6.

The channel 10 receives the shoe 19 through a longitudinal slot 22 formed by turning inwardly the top portions 24 of the channel walls. Within the restricted channel thus obtained, the shoe 19 is flared outwardly and downwardly and extended longitudinally of the channel at 25, forming a freely sliding fit with the channel walls. This prevents twisting of the follower plate 8 relative to the longitudinal axis of the drawer without interfering with adjustment therealong. The lower edge of the elongated shoe portion 25 is serrated at 26 to fit over an evenly spaced row of blisters or stops 27, punched upwardly from the bottom of channel 10 as shown in Fig. 5. These blisters 27 form two parallel saw-toothed racks extending the full length of channel 10, with their vertical faces 29 facing the front of the drawer, and their inclined faces 30 facing the rear.

The elongated shoe portions 25 are of sufficient vertical extent to prevent backward tilting of the follower plate 8 from disengaging the serrations 26 from the racks 27. When the follower plate is lifted vertically, however, the serrations 26 will clear racks 27, so that the shoe assembly 9 may be slid freely along the channel to any new plate position.

The longitudinal adjustment of the follower board within a drawer is accomplished by lifting the whole assembly approximately $\frac{1}{2}$ of an inch.

The mechanism for controlling the force applied in returning the follower plate to its normal vertical position after rearward tilting is shown in Figs. 3, 4, and 5. Two coil springs 40 are disposed around hinge pin 13, with the free end 41 of each engaging the rear side of plate 8. The opposite end of each spring is secured in a toothed or castellated collar 42 keyed to hinge pin 13 by a pin 44. A wrench shank 45 is formed on one end of hinge pin 13, and a wrench opening 46 is cut through the drawer side 5. In some cases it may be desirable to cut a number of such wrench openings 46 at intervals along the drawer.

When it is desired to adjust the spring pressure, the follower plate is moved along the drawer until the wrench shank 45 is aligned with a wrench aperture 46, and a wrench, not shown, but which may conveniently be of ordinary socket design, is inserted and the hinge pin 13 rotated, while at the same time a locking mechanism is held in released position, as will be described hereafter. When sufficient spring pressure has been obtained, the locking mechanism is allowed to function. In ordinary letter files, it is usually satisfactory to apply pressure varying from 6 to 8 pounds against the follower board with each spring, or a total pressure of between 12 and 16 pounds. For legal size files, the pressure runs about 12 pounds per spring, or a total pressure of 24 pounds. Extremely heavy material, such as X-ray films, catalogs, and the like may require a pressure in excess of these values. Any amount of pressure required, within reasonable limits, may be secured through proper adjustment of the springs.

Regardless of the magnitude of pressure exerted, the follower 8 is never permitted to incline forwardly of the vertical. A stop lug 50 formed

on shoe assembly 9 extends into an arcuate slot 51 cut into the center journal 15 of plate 8. Slot 51 has sufficient radial extent to permit backward tilting of the follower through an arc of substantially 25° from the vertical. If it is necessary to extend this range, the slot 51 may be increased in its radial dimension.

The pressure exerted by the springs 40 is held at any desired value by locking means which 10 may be instantly released when it is desired to change the force acting. Since the castellated collars 42 are fixed relative to hinge pin 13 by the key pins 44, turning the hinge pin 13 by a wrench as described above winds up or loosens 15 the coil springs 40, so that the free spring ends 41 exert greater or lesser pressure against the follower plate.

Castellated sleeves 60 are disposed slidably about hinge pin 13 adjacent each of the fixed 20 castellated collars 42 and arranged to interlock therewith. The sleeves 60 are attached to supporting plates 61 slotted at 62 parallel to hinge pin 13. The supporting plates 61 are in turn attached slidably to the follower plate 8 by two 25 large headed rivets 64 or equivalent elements passing loosely through the slots 62. The use of two rivets 64 with each supporting plate 61 insures movement parallel to hinge pin 13, eliminating binding and provides a stop limiting movement of the support plates when manipulated by finger grips 65 formed therein. When the finger grips 65 are squeezed toward each other, the 30 slidable castellated sleeves 60 are drawn out of engagement with the fixed castellated collars 42, and the springs 40 may be adjusted.

When finger grips 65 are released, a compressed coil spring 66 between them forces the castellated sleeves 60 to re-engage the castellated collars 42, thus locking springs 40 under the desired stress. 40 Spring 66 is held in alignment by a pin 67 fixed centrally thereof to one of the thumb grips 65 and passing slidably through the other grip 65.

In certain types of service it may be desirable to use in conjunction with the movable follower 45 plate one or more dividers, or record supports, set at intervals along the drawer, to separate different groups of files. A preferred form of divider is shown in my aforesaid Patent No. 2,272,537. An embodiment of such a type of divider which is suitable for use with the follower plate of the present invention is shown in Fig. 6, while Fig. 7 shows a modified form for such a record support.

The divider 70 is a flat plate having projecting 55 ears 71 on either side at the top which rest on the drawer sides 72 to limit the rearward slope while pivoting about feet 74 at the bottom. The feet 74 extend downwardly from the plate proper, and each has an ear 75 projecting toward the center. The ears 75 are set in apertured racks 76 disposed along the bottom near the edge at each side.

The particular configuration of the divider 65 rack apertures is no part of the present invention, and is shown here for exemplary purposes only. The rack mounting shown is not capable of use with the drawer and central channel illustrated in Figs. 1-5 of the present application, and so I have illustrated modified drawer forms in Figs. 6 and 7 which are suitable for use with the preferred form of divider rack.

Along each edge of a drawer bottom 77 which carries centrally a channel 10 in the rectangular seat 21, I form a depressed channel 79 of rectangular cross-section. The outer edge of chan-

nel 79 is defined by the drawer side 72, while the inner edge is defined by a channel wall 80 from which arrow-head apertures 81 are stamped to form part of divider rack 76. The remainder of divider rack 76 is formed by transverse slots 82 communicating with arrow-head apertures 81 and stamped from a horizontal reinforcing shoulder 84 pressed slightly downward from the level of drawer bottom 77. In some cases the depressed shoulder 84 may be omitted and the transverse slots 82 stamped directly from drawer bottom 77. It may then be desirable to increase the depth of arrow-head apertures 81 by an amount corresponding to the depressed depth of shoulders 84.

In use, the arrow-head apertures 81 provide a pivot for restricted rotation of divider 70 about feet 75. While there is a firm lock between the plate 70 and rack 76 in tilted positions of the former, the plate 70 may be readily removed in vertical position, the ears 75 sliding readily through the transverse slots 82.

In Fig. 7, a further modification in drawer form is shown in which the side channels 79 are moved to a position adjacent the central channel 20.

Here a central seat 90 is stamped from drawer bottom 91, with sufficient width to accommodate follower board channel 20 and a divider rack member 92. In this design the divider rack 92 is formed from a separate sheet of metal, and may be fixed in seat 90 and to follower channel 20 by any conventional means, not shown, such as screws or spot welds.

Divider rack 92 is formed by turning up inner sides 94 from a flat base 79 resting on central seat 90, bending inner sides 94 horizontally outward to form shoulders 96 in the plane of bottom 91, and bending outer sides 97 downwardly from shoulders 96 to fit snugly within side walls 99 of the central seat 90.

Arrow-head openings 81 are cut in inner divider rack sides 94 and transverse slots 82 communicating therewith are stamped through the horizontal shoulders 96 to complete the rack 92. Obviously these arrow-head openings 81 and slots 82 may be stamped by a single tool from a flat sheet prior to bending the sheet to form the sides and shoulders.

In this modification, the divider 100 is carried by a central foot member 101 having bifurcated portions 102 extending downwardly on each side of channel 20. An ear 104 extending outwardly from each bifurcated foot portion 102 is provided for engagement with the divider rack 92. The connection between rack 92 and divider 100 is identical in operation with that described above in connection with Fig. 6.

From the above description it will appear to those familiar with the construction of filing cabinets, that I have invented an improvement which contributes substantially to the rapidity, ease, and efficiency with which files may be used.

Contents of the drawer are kept in upright position under sufficient pressure to insure that they will be flat and neat, yet space is instantly available for inspection, insertion, or removal of files. Backward tilting and return of the files is accomplished without sliding the entire contents along the bottom of the drawer. The position of the follower board may be instantly changed to accommodate differing quantities of filed material, and the pressure exerted by the board to keep the files upright is readily adjusted to any desired value. Easily movable dividers are

provided to segregate various portions of the contents of the drawer, without interference with the operation of the follower in returning the contents to upright position after being tilted backward.

All movements of the file mechanism are accomplished without damage to the files themselves, and no working parts can come into contact with the contents of the drawer. At the same time, the design has been simplified and the number of necessary parts reduced so that the new construction effects considerable economies in manufacture.

It will be understood that the details of construction shown are exemplary only of my invention, and that I reserve the right to use equivalent elements wherever it is found desirable. While I contemplate making my drawer of the usual sheet metal and stamping construction, other methods of forming the parts, and the use of optional materials such as plastics are intended to be included in the scope of the claims.

What I claim is:

1. The combination, with a filing cabinet drawer having a longitudinally channeled bottom, of a shoe cooperating with said channeled bottom for temporary locking in any desired position lengthwise of said drawer, journals formed on said shoe arranged to receive a hinge pin transversely of said drawer and substantially in the bottom plane thereof, a follower board, journals formed along the bottom thereof staggered from said shoe journals, a hinge pin extending through said shoe and follower board journals, springs disposed about said pin fixed radially thereof at one end of said springs and having the opposite end bearing against said follower plate, means for adjustably fixing the pressure exerted by said springs against said follower plate.

2. The combination, with a filing cabinet drawer having a longitudinally channeled bottom, of a shoe cooperating with said channeled bottom for temporary locking in any desired position lengthwise of said drawer, journals formed on said shoe arranged to receive a hinge pin transversely of said drawer and substantially in the bottom plane thereof, a follower board, journals formed along the bottom thereof staggered from said shoe journals, a hinge pin extending through said shoe and follower board journals, toothed collars fixed on said hinge pin in staggered relation to said journals, springs disposed about said pin and having one end of each fixed radially of said pin in said toothed collar and having the opposite end of each engaging said follower board, cooperating teeth formed on adjacent ones of said follower board journals, and means for traversing said toothed follower board journals axially of said pin for normal engagement with said toothed collars while permitting disengagement thereof for rotation of said hinge pin.

3. In combination with a filing cabinet drawer and adjustable follower board substantially as described in claim 2, means for adjusting the pressure of said springs against said follower board without removing said board from said drawer, comprising an aperture formed in the side of said drawer, a wrench shank formed on said hinge pin, and means for withdrawing said toothed follower board journals from engagement with said toothed spring collars.
